UNITED STATES PATENT OFFICE.

ELMER B. JOHNSON, OF BLAIR, WISCONSIN.

SHAFT-CO尤LING FOR VEHICLES.

1,332,343.

Specification of Letters Patent.

Patented Mar. 2, 1920.

Application filed May 13, 1918. Serial No. 234,221.

To all whom it may concern:

Be it known that I, ELMER B. JOHNSON, a citizen of the United States, residing at Blair, in the county of Trempealeau, State 5 of Wisconsin, have invented certain new and useful Improvements in Shaft-Couplings for Vehicles; and I do hereby declare the following to be a full, clear, and exact description of the invention, such as will enable others skilled in the art to which it 10 appertains to make and use the same.

This invention is an improvement in running gear for vehicles and has particular reference to a shaft coupling for binder and 15 mower trucks.

An object of the invention is to provide an improved coupling of simple, effective and inexpensive construction whereby a shaft or tongue may be connected to the 20 draw bar of a vehicle at two points and yet in such manner as to permit of a relative movement between said parts when the vehicle is traveling over uneven ground.

The inventive idea involved is capable of 25 receiving a variety of mechanical expressions one of which, for the purpose of illustrating the invention, is shown in the accompanying drawing wherein:—

Figure 1 is a side elevation of the coupling 30 showing the same attached to the draw bar of a binder or mower truck.

Fig. 2 is a longitudinal sectional view therethrough.

Fig. 3 is a detailed perspective view of the 35 coupling.

Referring more particularly to the accompanying drawing in which like reference characters indicate similar parts, the numeral 5 indicates the draw bar of a binder 40 or mower truck to which the shaft or tongue 6 is adapted to be connected although it will be understood that the connection may be utilized for the purpose of securing together the shafts and draw bars of other machines 45 or vehicles other than those above mentioned.

The coupling is shown in what is now believed to be its preferred form. A single sheet of any desirable material is bent along 50 parallel lines to provide a substantially U-shaped body portion 7 which forms a channel for receiving the outer or forward extremity of the draw bar 5 and said draw bar

is secured in the body portion by means of the bolts or other fasteners 8 extending 55 transversely through the draw bar and the sides of the body portion. At their forward ends the sides of the body portion 7 are extended beyond its bottom to provide the shaft supporting plates 9 arranged in 60 spaced parallel relation with respect to each other and said plates are preferably made of a width substantially the same as that of the sides of the body portion. These plates are provided adjacent their inner ends with 65 the oppositely disposed holes 10 for receiving a pivot pin 11 which extends through the inner end of the shaft 6 mounted between said plates whereby to pivotally connect the shaft to the coupling and draw bar 70 in such manner as to permit of a vertical swinging movement of the shaft. Adjacent the outer ends of the plates 9 the same are provided with transverse vertically disposed slots 12 struck on arcs around said 75 holes. In the slots are movable laterally extending pins 13 in the shaft 6 whereby the swinging movement of the shaft will be limited by engagement of the pins 13 with the ends of said slots. By reason of the 80 relative movement between the shaft and draw bar it will be apparent that excessive movements of the vehicle and consequently the draw bar will not be transmitted to the shaft when the vehicle is traveling over uneven ground and strains upon the draft animals which would be otherwise occasioned if the shaft were rigidly connected to the draw bar will thereby be avoided.

By this construction it will be seen that 90 the draw bar is connected with the body of the coupling by two bolts 8 as shown herein, and it is possible to use additional bolts or fastening means if desired. Also the tongue or shaft is connected with the plates of the 95 coupling by two elements such as the bolts or pins 11 and 13, and draft on this member is transmitted to the bar 5 through several points. In other words, pull on the shaft is communicated through the bolts or pins 11 100 and 12 to the plates 9 and the body 7, and by the latter through the bolts 8 and 8 to the tongue 5; and if the vehicle should be backed by the team, the push of the latter will also be communicated through these 105 several points. In one action the shaft

draws the rear edges of the slots against the pins 13, and in the other action the shaft pushes their front edges against said pins, this result flowing from the fact that the slots are struck on arcs around the pivot pin 11.

The invention also includes means for further relieving the strain upon the draft animals due to the weight of the draw bar and forward part of the machine and, to this end, the forward end of the draw bar has depending therefrom and extending through the bottom of the body portion 7 a pivot 14 upon which is revolvably mounted a bearing 15 having the forks 16 depending therefrom and carrying a shaft 17 at their lower ends upon which is mounted a ground wheel 18 adapted for engagement with the ground whereby to support the weight of the draw bar and forward part of the machine in such manner as to relieve the draft animals of

this weight and the consequent strain which would be incident thereto.

What is claimed is:—

The herein described shaft coupling comprising a channeled body in which the front end of the draw bar of a vehicle is bolted, the sides of said body being continued forward in parallel plates spaced to receive the rear end of the shaft, the plates having opposite holes forward of the body and opposite slots forward of the holes and struck on arcs around said holes, a pivot pin through the holes and shaft, and pins in said shaft movable in said slots, for the purpose set forth.

In testimony whereof I affix my signature in the presence of two witnesses.

ELMER B. JOHNSON.
